UNITED STATES PATENT OFFICE.

JESSE D. LANGDON, OF LOS ANGELES, CALIFORNIA, ASSIGNOR TO GRACE NORRIS,
OF GUTHRIE, OKLAHOMA.

DEVICE FOR PUTTING PERMANENT WAVES IN HAIR.

Application filed August 4, 1926. Serial No. 127,103.

The present invention relates to devices for putting permanent waves in hair, and aims to provide a novel and simple device for that purpose which is simple, practical 5 and efficient in use.

Another object of the invention is the provision of such a device which will put permanent waves in hair by a frictional rubbing and clamping action, without requiring heat, 10 and by means of which the structure of the hair is deformed to put permanent waves therein.

A further object is to provide a device of the kind indicated comprising two members 15 adapted to be moved together with the hair between them and formed with novel portions adapted to engage one another and operate on the hair between them in such a manner as to put the waves in the hair.

With the foregoing and other objects in view, which will be apparent as the description proceeds, the invention resides in the construction and arrangement of parts, as 20 hereinafter described and claimed, it being understood that changes can be made within 25 the scope of what is claimed, without departing from the spirit of the invention.

The invention is illustrated in the accompanying drawing, wherein—

Figure 1 is a side elevation of the device, 30 portions being shown in longitudinal section.

Fig. 2 is an enlarged cross section on the line 2—2 of Fig. 1.

Fig. 3 is a cross section on the same line 35 as Fig. 2 showing the parts moved together.

In carrying out the invention, there is provided a channel-shaped member 7 of sheet metal or other suitable material which has 40 the bottom 8 and sides 9, and the sides 9 are provided with the inturned flanges 10 provided with the depending secondary flanges 11 extending toward the bottom 8. Within the member 7 is disposed a pair of 45 elongated plates or strips 12 of sheet metal or other suitable material, extending longitudinally along the flanges 11 and across the edges of said flanges. The plates 12 are provided at their opposite edges with outstanding flanges 13 overlapping the flanges 11 behind same, and the plates 12 are provided 50 at their adjacent edges with the rounded beads or portions 14. The plates 12 are thus disposed across the longitudinal opening or slot between the flanges of the shell or mem-

ber 7, and the beads 14 are normally spaced slightly to permit the hair to be withdrawn from between them.

A core or filler 15 of rubber or other compressible or resilient material is disposed 60 within the member or shell 7, and provides a cushion below the plates 12 to yieldingly support said plates in their normal common plane, as seen in Fig. 2. The core or cushion 15 has a longitudinal groove 16 65 therein below the space or slot between the adjacent edges of the plates 12 and the beads 14 overlap the opposite walls of the groove 16 along the edges of said groove.

The elements above described constitute 70 one part or member of the device, and the other part or member of the device comprises a bar or lever 17 having a blade 18 adapted to enter the firstnamed part of the device. As shown, the two parts are hingedly connected 75 at one end. Thus, the flanges 10 have outstanding ears 19 between which the corresponding end of the bar or lever 17 is pivoted, as at 20, and the adjacent end portion of the blade 18 is rounded off, as at 21, so 80 as to conveniently enter and leave the slot between the plates 12. The member or shell 7 and lever 17 are provided at the ends thereof opposite to the hinge with the handles 22 and 23, respectively, whereby the two 85 parts or members may be conveniently moved together and apart by hand.

The blade 18 may be of suitable thickness, and its edge is rounded, in order to put a wave or kink of desired magnitude in the 90 hair.

In using the device, the two parts are separated and a suitable number of strands of hair are brought between the two parts with the strands extending transversely across the 95 flanges 10 and slot between them. The handles 22 and 23 are then moved toward one another, which will forcibly move the blade 18 between the plates 12, and in doing so the plates 12 are pushed downwardly at their adjacent edges and are separated, as seen in 100 Fig. 3. The depression of the plates 12 will also compress the core or cushion 15, and the groove 16 will receive the edge portion of the blade.

The hair is bent across the edge of the blade 18, as said blade passes between the plates 12, and the loops of hair thus formed are forced downwardly between the plates 12, and move with a frictional rubbing 110

action across the adjacent rounded edges or portions 14 of the plates 12 during which the plates 12 are pressed by the cushion or core 15 tightly against the opposite sides 5 of the blade 18, and this action will deform the structure of the hair in a way to obtain a permanent wave in each strand of hair. The waves are thus set permanently in the hair, and after the parts are separated so 10 as to withdraw the blade 18 from between the plates 12, the hair may be withdrawn. The operation is repeated for the same strands of hair if a series of waves are desired. It will be noted that when the blade 15 has been forced between the plates 12, so 15 that said plates are swung inwardly as seen in Fig. 3, said plates will resist the withdrawal of the blade by a toggle action, the flanges 13 of the plates bearing against 20 the cushion or core 15 to yieldingly move the plates against the blade. Thus, when the blade is withdrawn there is a tendency to swing the plates outwardly with the blade, thereby producing a further frictional rub- 25 bing and clamping action between the blade and plates to effectively deform or distort the structure of the hair. This action is even more effective than the action which takes place when the blade is moved be- 30 tween the plates, because the pressure be- 35 tween the blade and plates is greater due to the fact that the plates tend to swing together while the blade is being withdrawn.

Having thus described the invention, what 35 is claimed as new is:—

1. A device of the character described comprising a pair of members, a blade movable between them, and means for yieldingly mounting said members so that they may be 40 swung by the contact of the blade with said members and may be separated when the blade is forced between said members.

2. A device of the character described comprising one part having a pair of yieldingly-mounted members, and another part 45 having a portion to move, with hair between said parts, between said members with a frictional rubbing and clamping action, said members being arranged to be forced apart 50 by said portion when said portion is moved between them.

3. A device of the character described comprising one part having a pair of yieldingly-mounted plates, and another part

having a blade movable between the adjacent edges of said plates, said plates being arranged to be forced apart by said blade when the blade is moved between them. 55

4. A device of the character described comprising a shell having a slot, a pair of plates disposed across said slot, yieldable means in the shell supporting said plates, and a blade movable between said plates, said plates being arranged to be forced apart by said blade when the blade is moved between said plates. 60

5. A device of the character described comprising a shell having a slot, a pair of plates disposed across said slot and adapted to swing inwardly at their adjacent edges, 70 a yieldable cushion in said shell supporting said plates, and a blade movable between said plates, said plates being arranged to be forced apart by said blade when the blade is moved between said plates. 75

6. A device of the character described comprising a channel-shaped shell having inturned flanges provided with secondary flanges extending into the shell, a pair of plates extending across the space between 80 said flanges and having outwardly extending flanges at their opposite edges engaging behind the secondary flanges, a yieldable cushion in said shell supporting said plates, and a blade movable between said plates, 85 said plates being arranged to be forced apart by said blade when the blade is moved between said plates.

7. A device of the character described comprising a pair of yielding members, and a blade movable between them, with hair between said members and blade, with a frictional rubbing and clamping action, said members being arranged to be forced apart by said blade when the blade is moved between said members. 90

8. A device of the character described comprising a shell, a pair of plates mounted yieldingly therein and having adjacent edges, and a blade movable between said 100 edges of the plates with a frictional rubbing and clamping action, said plates being arranged to be forced apart by said blade when the blade is moved between said plates.

In testimony whereof I hereunto affix my 105 signature.

JESSE D. LANGDON.
